UNITED STATES PATENT OFFICE

2,453,581

CLUTCH AND BRAKE DEVICE

George E. Moore, Muskegon Heights, Mich., assignor to Manning, Maxwell & Moore, Inc., Muskegon Heights, Mich., a corporation of New Jersey

Application May 17, 1945, Serial No. 594,239

8 Claims. (Cl. 192—16)

1

The invention relates to hoists generally, and more particularly to portable chain hoists.

One object of the invention is to provide an improved hoist of the above general character embodying novel features of construction which particularly adapt it for operation by means of a hand lever.

Another object is to provide improved brake mechanism suitable for both manual and power driven hoists which is simple in construction, quiet in action and efficient and reliable in operation.

Another object is to provide improved means whereby the load chain of the hoist may be lowered positively by the drive mechanism when desired.

Still another object is to provide novel means for temporarily disabling the lifting mechanism so that the load chain may be pulled through the hoist in either direction by hand.

Other objects and advantages of the invention will become apparent from the following detailed description of the preferred embodiment illustrated in the accompanying drawings in which:

Figure 1 is a side view of a chain hoist embodying the features of the invention;

Figure 2 is a transverse sectional view of the hoist taken in a horizontal plane substantially on the line 2—2 of Figure 1;

Figure 3 is a sectional view taken in a vertical plane substantially on the line 3—3 of Figure 2;

Figure 4 is a sectional view taken in a vertical plane substantially on the line 4—4 of Figure 2;

Figure 5 is a sectional view taken in a vertical plane substantially on the line 5—5 of Figure 2 showing the parts set to condition the load brake for ordinary lifting operations; and

Figure 6 is a sectional view similar to Figure 5, but showing the parts set to release the load brake.

While the invention is susceptible of various modifications and alternative constructions, I have shown in the drawings and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claims.

For the purpose of illustration, the invention has been shown as embodied in a portable hoist of the type adapted to be actuated by a hand lever (Figures 1 and 2) but it will be understood that the invention, in several of its aspects, is

2

applicable to other types of hoists. The exemplary hoist comprises a generally cylindrical housing or body 11, conveniently formed as a hollow casting, adapted to be supported by a suitable hook 12 having a swivel mounted in the upper part of the housing as shown in Figure 3. In a commercial structure the housing 11 will be made in at least two parts so that access to the interior thereof for assembly purposes will be facilitated.

Rotatably supported within the housing 11 by antifriction bearings 13 is a lifting member or load wheel 14 shaped to accommodate a suitable load chain 15. In the particular hoist shown, the wheel 14 is formed with a pocketed circumferential groove 16 shaped to receive a conventional link type chain. The load wheel is located within a downwardly opening recess or pocket 17 (Figure 3) through which the chain 15 depends and is preferably disposed so that the load supporting run is substantially aligned with the hoist supporting hook 12. The chain is provided at its load carrying end with the usual load hook 18 while the other end is secured to a lug 19 preferably cast integrally with the housing 11. Proper engagement of the chain links with the load wheel pockets is insured by a guide slot 20 formed in the part of the housing 11 defining the walls of the recess 17.

The load wheel 14 is adapted to be rotated for lifting purposes by drive mechanism including a load shaft 21 rotatably supported in the housing 11 with its axis substantially parallel to the axis of the load wheel. As shown in Figure 2, the shaft 21 extends through a bushing 22 rigidly fitted within the housing 11 and is journaled in needle bearings 23 seated in the bushing. At its inner end, the shaft is provided with a rigid pinion 24 meshing with gear teeth 25, herein shown as formed integrally with the load wheel 14.

The load shaft 21 is adapted to be driven by a rotatable driving member or nut 26 through the medium of a friction device 27 which additionally functions as a load brake to prevent retrograde movement of the shaft and load wheel 14 under load. For this purpose, the driving member 26 is formed with an internally threaded bore adapted to engage with relatively coarse external threads 28 formed on a collar 29 keyed to the shaft 21 and having a rigid thrust disk 30 at its inner end. If desired, the threaded collar and thrust disk may be formed integrally with the shaft.

Loosely mounted on the collar 29 between the member 26 and the thrust disk 30 is a ratchet

wheel 31 having a cooperating pawl 32 (Fig. 4) pivotally supported by a pin 33 in an auxiliary housing 34 rigidly secured to one end of the housing 11. A friction washer 36 interposed between the ratchet wheel 31 and the thrust disk 30 and a second friction washer 37 interposed between the ratchet wheel and a thrust ring 38 rigid with the driving member 26 provide a disengageable connection between the parts. Thus when the member 26 is rotated in a load lifting direction, it screws along the threads 28 on the load shaft 21 compressing the friction washers 36 and 37 against the thrust disk 30 until its axial movement is blocked whereupon it rotates the shaft in a direction effective to raise the load carrying end of the chain 15.

Referring now to Figure 4 of the drawings, it will be observed that the pawl 32 is provided with a finger 32a positioned to coact with peripheral teeth 39 formed on the ratchet wheel 30 to prevent rotation of the wheel in a counterclockwise or load lowering direction. The ratchet teeth are formed however and the pawl finger 32a is so disposed that the ratchet wheel may be rotated in a load lifting direction without interference from the pawl.

To reduce friction and provide quiet action in the lifting operation, and to insure positive locking of the ratchet wheel after such operation, means is provided for swinging the pawl 32 into or out of engagement with the teeth 39 of the ratchet wheel. This means, as shown in Figures 2 and 4, comprises an arcuate clamping member 40 of heavy gauge wire or the like anchored at one end to the pawl 32 by means of a pin 41 and partially encircling the thrust disk 30. To retain the clamping member in place, the disk is conveniently formed with a peripheral groove 42. When the shaft 21 is turned in a load lifting direction, that is clockwise as viewed in Figure 4, the member 40 tends to rotate with the thrust disk and is thus effective to rock the pawl 32 clear of the teeth of the ratchet wheel. Upon rotation of the shaft in the opposite direction, the clamping member is carried along and the pawl is positively rocked into blocking engagement with the ratchet teeth thus effectually preventing any more than the slight rotation of the ratchet wheel required for the engagement of the pawl finger with the ratchet teeth.

The locking of the ratchet wheel 31 in the above manner permits the friction device 27 to function as a load brake effective to prevent undesired lowering of a load. The load, acting through the wheel 14, tends to turn the shaft in a counterclockwise direction as viewed in Figure 4. Assuming that the driving member 26 is held stationary, such rotation of the shaft acts to screw the member along the threads 28 and thus frictionally clamp the ratchet wheel to the thrust disk 30 which, as explained heretofore, is rigid with the shaft 21. As the ratchet wheel is locked against counterclockwise rotation, turning of the load shaft under the influence of the load is effectually prevented.

When lowering the load is required, it is only necessary to rotate the driving member 26 reversely relative to the shaft 21, thus backing it along the shaft sufficiently to disengage the friction washers from the ratchet wheel and thrust disk thereby releasing the load brake. As the shaft 21 turns, it tends of course, to screw the driving member up to brake engaging position therefore necessitating a constant turning of the driving member during such lowering action.

The lowering may be stopped at any time by simply interrupting the rotation of the member whereby the member will be screwed against the friction elements thus initiating the braking action as above described.

Provision is made for positively driving the shaft 21 in the load lowering direction in case the load on the chain 15 is too light to effect the lowering in the manner above described. For this purpose, the shaft 21 is provided at its outer end with a drive collar 45, non-rotatably fixed to the shaft as by splines 46. The collar 45 is formed with a radially projecting arm 47 extending over the adjacent end of the driving member 26 and adapted for engagement by a lug 48 projecting axially from the end of the driving member. In the ordinary operation of the hoist, the action of the load on shaft 21 keeps the arm 47 spaced substantially from the lug 48 as shown in Figure 5. When the load is insufficient to turn the shaft, however, rotation of the driving member 26 in the load lowering direction carries the lug 48 into engagement with the arm 47 as shown in Figure 6 whereby the shaft is positively driven upon further rotation of the driving member.

In practice, the parts are adjusted so that rotation of the drive member 26 through a relatively small angle is sufficient to engage or release the friction elements of the load brake 27. The normal range of such movement is indicated by relative positions of the lug 48 and arm 47 in Figures 5 and 6 respectively. The range of movement increases progressively as the friction washers 36 and 37 wear. Provision is therefore made for adjusting the angular position of the collar 45 relative to the shaft 21 so as to maintain the desired spacing between the lug 48 and arm 47 substantially as shown. For this purpose, the collar is formed with a plurality of circumferentially spaced grooves 49 engaging with the splines 46 to lock the collar to the shaft.

Novel means is provided for temporarily rendering the load brake 27 ineffective so that the chain 15 may be pulled through the hoist in either direction by hand. To this end, provision is made for locking the driving member 26 to the collar 45 in a position to effect the release of the load brake and to cause the driving member to rotate with the shaft 21 and collar when the chain is pulled to either raise or lower the hook 18.

The locking means, in its preferred form, comprises a flat elongated spring element 50 rigidly secured as by rivets 51 at two circumferentially spaced points within a cup-shaped hand wheel 52 rotatably supported on the outer end of the load collar 45 and the driving member 26. One of the rivets 51 is located closely adjacent the end of the element and the section of the element between that rivet and the adjacent rivet is bent inwardly to provide a radial shoulder 54 adapted to engage the arm 47 for rotating the collar 45 and shaft 21 when the hand wheel 52 is turned in a clockwise direction (as viewed in Figures 5 and 6).

The free end of the spring element 50 is extended a substantial distance around the peripheral wall of the hand wheel so as to provide a resilient section adapted to ride over the outer surface of the lug 48 upon rotation of the hand wheel as above described. A nib or projection 55 formed in the element engageable in a notch 59 in the lug when the hand wheel is turned to the position shown in Figure 6 acts to lock the parts together. When so locked, the friction device 27 is disengaged, thus freeing the shaft 21 from the load brake so that it may rotate freely in either

direction. Accordingly, the chain 15 may be pulled through the hoist in either direction by hand without interference from the brake.

The above described elements of the hoist are adapted to operate in the manner set forth irrespective of the particular means utilized for rotating the driving member 26. When manually operated means, such as the hand lever 10, is employed for that purpose, as in the exemplary hoist, the operating connection between the lever and the member 26 is preferably in the form of a pawl and ratchet mechanism. The member 26 may conveniently constitute the ratchet wheel of the mechanism and to this end is provided with peripheral teeth 60 suitably shaped for coaction with a pawl.

As herein shown, the hand lever 10 is constructed of sheet metal and is formed at one end to provide an enlarged, generally circular casing section 62 apertured to fit over the member 26. Flanged rings 63 and 64 (Figure 2) fitted within the aperture and seated on the member 26 on opposite sides of the ratchet teeth 60 support the handle for rotation relative to the member. Preferably, the end or casing forming portion of the handle is open at one side and is arranged to be closed by a removable cover plate 65 providing access to the interior of the casing.

For cooperation with the ratchet teeth 60 of the member 26, the handle 10 is provided with a pawl 66 (Figures 1 and 2) adapted to be set manually for turning the member 26 in either a load lifting or load lowering direction. Alternatively, the pawl may be set in a neutral position in which it is disengaged from the teeth 60 when it is desired to pull the chain through the hoist by hand. As herein shown, the pawl 66 is in the form of a steel disk having a segment cut away at one side to define a pair of laterally spaced tooth like pawl elements 67 and 68 individually engageable with the ratchet teeth 60. Trunnions 69 projecting at opposite sides of the pawl disk and engaging in bearings 70 carried by the back wall of the handle 10 and the cover plate 65 support the pawl for rocking movement about an axis parallel to the axis of the member 26 whereby the pawl elements 67 and 68 may be engaged selectively with the teeth 60.

Means is provided for rocking the pawl 66 between either of the active positions above referred to and the neutral position and for yieldably holding it in such positions. This means in its preferred form includes a pair of torsion springs 71 and 72 coiled about a pin 73 anchored in the handle 10 at one side of the pawl 66 and having their opposite ends engaged respectively with a pin 74 fixed to the handle and a pin 75 extending across a slot 76 in the back of the pawl 66. The springs are coiled in opposite directions on the pin 73 and their projecting ends are positioned on opposite sides of the pins 74 and 75 so that each spring tends to rock the pawl against the force exerted by the other.

The shifting of the pawl between its various positions is preferably effected by manually operable means such as a thumb lever 77. For this purpose, the lever is pinned or otherwise rigidly fixed on the projecting end of a shaft 78 journaled in the handle 10 between the spring supporting pin 73 and the pawl 66. The shaft 78 is formed with an eccentric section 79 disposed between the ends of the springs 71 and 72, the eccentric section being of substantially the same diameter as the pin 75. With the thumb lever in the posi-

tion shown in Figure 1, the eccentric 79 is located in line with the pin 75 and the spring ends are permitted to act on opposite sides of the latter pin so as to hold the pawl in the neutral or disengaged position. When the thumb lever 77 is rocked away from the neutral position, the eccentric 79 forces one or the other of the spring ends away from the pin 75 thus enabling the other spring to rock the pawl to its active position. The pawl is thus yieldably held in a selected operated position so that it is effective to turn the ratchet wheel when the handle 10 is rocked in one direction and to slide over the ratchet teeth when the handle is rocked in the opposite direction. Thus the pawl may be set in either of two operated positions for lifting or lowering a load or it may be set in a neutral position or temporarily disabled position so that the load chain can be pulled through the hoist by hand.

It will be apparent from the foregoing that the invention provides a portable hoist of novel and advantageous construction. Through the provision of novel means for temporarily disabling the load brake and drive mechanism, the hoist may be adjusted so that the load chain can be pulled therethrough in either direction by hand. Provision is also made so that the load chain may be positively lowered through the operation of the driving mechanism which is advantageous in adjusting the position of the chain without a load thereon.

The improved hoist embodies novel brake mechanism which is simple in construction, quiet in action and efficient and reliable in operation.

While the various novel structural features of the hoist lend themselves particularly well to manual hoists of the lever type, they are also well suited for other types of hoist. As to the particular operating mechanism employed in the exemplary hoist, it will be observed that the improved pawl and ratchet mechanism enables the load shaft to be turned in either direction by appropriate operation of the hand lever. Furthermore, the driving mechanism may be completely freed from the hand lever when desired.

What is claimed is:

1. In a hoist, in combination, a load shaft, a driving member mounted on said shaft for rotation relative thereto, a load brake for said shaft, means operable in response to the relative rotation of said member and shaft in one direction for rendering said brake effective to prevent rotation of said shaft in a load lowering direction, said brake being released upon relative rotation of said member and said shaft in the opposite direction, and means operable to releasably latch said member and said shaft together in a position to maintain said brake released.
2. In a hoist, in combination, a load shaft, a driving member mounted on said shaft, a load brake, friction members operable when engaged to render said brake effective to prevent rotation of said shaft in a load lowering direction, said members being engaged and disengaged by relative rotation of said driving member and said shaft between two different positions, and manually operable means for latching said driving member and said shaft in a position in which said friction members are disengaged whereby to permit free rotation of said shaft in either direction.
3. In a hoist, in combination, a load shaft, a driving member mounted on said shaft, a load brake, friction members operable when engaged

to render said brake effective to prevent rotation of said shaft in a load lowering direction, said members being engaged and disengaged by relative rotation of said driving member and said shaft between two different positions, an arm rigid with said shaft and projecting radially therefrom, a lug rigid with said driving member adapted to engage said arm upon relative rotation of said member and said shaft to disengage said friction member, and manually operable means coacting with said arm and said lug for releasably latching said member and said shaft in a position to maintain disengagement of said friction members.

4. In a hoist, in combination, a load shaft, a driving member mounted on said shaft for rotation relative thereto, means operable in response to the relative rotation of said member and said shaft for effecting relative axial movements of the member and shaft, a load brake including a member rotatable in one direction only and adapted to be frictionally clamped to said driving member and said shaft by such relative axial movement in one direction, said brake member being released by relative axial movement of the member and the shaft in the other direction, and means operable to lock said member and said shaft together to maintain said brake member released.

5. In a hoist, in combination, a load shaft, a driving member mounted on said shaft for rotation relative thereto, means operable in response to the relative rotation of said member and said shaft for effecting relative axial movements of the member and shaft, brake means adapted to be engaged by such relative axial movement in one direction for preventing rotation of said shaft in one direction, said brake means being disengaged by relative axial movement of the member and the shaft in the other direction, an arm rigid with said shaft and projecting radially therefrom to overlie one end of said member, an axial projection at said one end of the member adapted to engage said arm upon relative rotation of the member and the shaft to disengage said brake means, and manually operable means coacting with said arm and said projection to hold them in engagement whereby to prevent reengagement of said brake means.

6. In a hoist, in combination, a load shaft, a driving member mounted on said shaft for rotation relative thereto, means operable in response to the relative rotation of said member and said shaft for effecting relative axial movements of the member and shaft, brake means adapted to be engaged by such relative axial movement in one direction for preventing rotation of said shaft in one direction, said brake means being disengaged by relative axial movement of the member and the shaft in the other direction, an arm rigid with said shaft and projecting radially therefrom to overlie one end of said member, an axial projection on said one end of the member adapted to engage said arm upon relative rotation of the member and the shaft to disengage said brake means, a hand wheel rotatably supported on said shaft, means carried by said hand wheel operable on the rotation of the wheel to turn said shaft so as to move said arm into engagement with said projection, and other means carried by said hand wheel operable to frictionally engage said projection to maintain said arm in engagement therewith.

7. In a hoist, in combination, a load shaft, a

driving member having a screw threaded connection with said shaft, a thrust disk rigid with said shaft and spaced from one end of said member, a ratchet wheel mounted on said shaft between said disk and said member, a pawl coacting with said wheel to prevent rotation in one direction, friction washers interposed between said member and said wheel and between said wheel and said disk, said member operating through said washers upon relative rotation of the shaft and member to frictionally clamp the parts together whereby rotation of the shaft is permitted only in a load lifting direction, a collar fast on said shaft, an arm rigid with said collar projecting radially therefrom to overlie the other end of said member, a radial projection on said member engageable with said arm upon relative rotation of the shaft and member to disengage the parts, a hand wheel rotatably mounted on said shaft, a spring member mounted in said hand wheel having a shouldered portion adapted to engage said arm and an arcuate portion adapted to slide over said projection, said shouldered portion being operative on rotation of the hand wheel for effecting relative rotation of the driving member and the shaft so as to move said arm and said projection into engagement, and detent means formed on the arcuate portion of said spring member adapted to coact with said projection to frictionally hold the projection and the arm in engagement.

8. In a hoist, in combination, a load shaft, a driving member mounted on said shaft for rotation relative thereto, means operable in response to the relative rotation of said member and said shaft through a predetermined angle in one direction to shift said member axially of the shaft, means operable by said member incident to such axial shifting for establishing a frictional driving connection between the member and the shaft whereby the member and shaft may be rotated together to lift a load, said connection being interrupted by reverse rotation of said member relative to said shaft through said predetermined angle, means operative to prevent reverse rotation of said shaft under the influence of a load while said connection is maintained, a collar mounted on said shaft having a rigid arm projecting laterally to overlie one end of said member, an axial projection at said one end of the member adapted to engage said arm to provide a positive driving connection between the member and said shaft, and means for locking said collar against rotation relative to said shaft, said locking means being adjustable to compensate for wear of the means providing the frictional driving connection between the member and the shaft.
